HORACE H. BURDETT, OF HOPEDALE, MASSACHUSETTS, ASSIGNEE TO DRAPER CORPORATION, OF HOPEDALE, MASSACHUSETTS, A CORPORATION OF MAINE

INTERMITTENT THREAD-CUTTING LOOM TEMPLE

Application filed October 7, 1929. Serial No. 297,768.

This invention relates to a thread cutting temple for looms of that type in which the cutting mechanism is not in continuous operation but operates intermittently for a predetermined time upon the occurrence of a predetermined condition, such as filling replenishment. The main object in having an intermittent action of thread cutting loom temple is to save wear and tear upon the filling cutting mechanism. Such a mechanism is only called upon to act at infrequent periods in the loom operation. If it is in operation continuously, it becomes worn, may become maladjusted, and thus may fail properly to perform its functions when they are required.

The object of the present invention is to provide a simple and efficient form of intermittently acting filling end cutting or parting mechanism such as is usually associated with a temple. The object of the invention is further to provide such a mechanism so constructed that when it is in inoperative position, it will not have even a slight movement and will be out of reach of the actuating instrumentality such as the lay.

The object of the invention is further to provide such an intermittently acting filling end cutting mechanism as will have a wide field of action when in operation so as surely to sever the filling ends extending from the selvage.

These and other objects and features of the invention will appear more fully from the accompanying description and drawings and will be particularly pointed out in the claims.

As the general location, purpose, and function of the thread cutting temple and the parts of the loom associated therewith are well known and familiar to those skilled in the art, it will only be necessary here to illustrate and describe those features directly concerned with the present invention. It will also be assumed that a preferred form of the invention is shown adapted for use in automatic filling replenishing loom such as the well known Northrop loom.

In the drawings:

Fig. 1 is a side elevation partially in vertical cross section of the thread cutting loom

temple embodying a preferred form of the invention and certain adjacent parts of the loom, the filling cutting mechanism being shown in operative position.

Fig. 2 is a view generally similar to Fig. 1 with the filling cutting mechanism in inoperative position.

Fig. 3 is a top plan view of the temple and filling cutting mechanism shown in Figs. 1 and 2.

Fig. 4 is a view chiefly in transverse section taken on the line 4—4 of Fig. 3.

Fig. 5 is a view in cross section taken on the line 5—5 of Fig. 4.

Fig. 6 is a view similar to Fig. 5 showing a different position of the detent cam.

In an automatic filling replenishing loom it is necessary to sever the filling ends left extending from the selvage both by the substantially exhausted filling carrier and by the incoming fresh filling carrier in order to give the proper appearance to the cloth and to prevent such ends from being whipped or thrown into the shed and thus producing imperfect cloth. The filling end cutting mechanism employed for this purpose is usually carried by or associated with the temple because the temple affords a convenient means and usually the only practical means for supporting such mechanism in the required position.

In the drawings, the breast beam 1, the lay 2, and the controller shaft or starting rod 3 may represent well known features of the Northrop automatic filling replenishing loom. When filling replenishment is to take place, the starter rod 3 is rocked counter-clockwise to bring this mechanism into action and it is desirable, in the case of an intermittently acting filling end severing mechanism, that the operation of the filling severing mechanism then take place and that there be a plurality of operations for a brief period to take place to insure that the filling ends be severed.

A loom temple of an ordinary type is shown at the right-hand side of the loom. This temple comprises a box-like stand 4 secured by bolts passing through the slot 5 in the flange base 6 to a bracket 7 suitably mounted on the breast beam and a support mounted to

move forward and rearward in the stand. This support is in the form of an extended hollow shank 8 mounted to slide in the stand 4. It is yieldingly projected rearward by a coiled spring 9 and is moved slightly forward by the lay 2 upon the beat-up engaging a heel 10 depending from the forward portion of the shank.

This support 8 presents at its rearward end 10 the usual temple head 11 with the enclosed temple roll 12 and this device may be of any desired type.

The cutting mechanism illustrated is of the general type shown in the patent to Draper et al., No. 1,361,839, December 14, 1920. It comprises a main cutter blade shown as a steel insert 13 set diagonally in a shank 14 mounted and rectilinearly movable on the support 8 of the temple and a cooperating cutter blade 15 opened and closed upon the main blade by the movement thereof forward and rearward. The shank 14 of the main cutter blade is provided near its end with the longitudinal slots 16 and 17 by which it is mounted and guided on the studs 18 and 19 threaded into the support 8. At the rearward end the stud 19 is provided with a fibre or friction washer 20 resting against the shank 14 of the blade and with an overlying spring washer 21 so that a light friction may be imposed upon the sliding movement of the blade. The shank 14 of the main cutter blade has depending therefrom at the rearward end a heel 22 alongside the heel 10 by means of which the forward movement of the cutting mechanism is imparted thereto by the lay 2. A spring 23 is connected at its forward end to a stud 24 on the shank 14 and at its rearward end to the stud 19 and acts yieldingly to effect the rearward movement. The cooperating cutter blade 15 is pivoted at 25 on the inner face of the shank 14 of the main cutter blade and is provided with an elbow-shaped slot 26 riding over the stud 19 so constructed that, when the main cutter blade is moved forward, the blade 15 will swing to open position, as shown in Fig. 2, and, when the main cutter blade moves rearward, will swing to closed position, as shown in Fig. 1. Thus as the main cutter blade is moved forward by the lay 2 and rearward by the spring 23, the cutting mechanism is first opened and then closed upon the filling ends extending within its field of action.

A mechanism such as thus far described would operate at each beat-up of the lay, whereas it is only necessary that its operation shall take place upon occurrence of some predetermined condition such as filling replenishment and then only for a brief period to insure the severance of the filling ends. The invention provides for this by a simple and efficient construction, first, by locking the filling cutting mechanism in an inoperative position, except when its operation is actu-

ally required, and, second, by locking it in such inoperative position that it will not be subject even to a slight movement from the lay or other actuating element. Thus there is no wear and tear upon the filling cutting mechanism except that actually required to enable it to perform its functions and thus the mechanism is maintained in good order ready for action when required.

In the preferred construction illustrated for securing the foregoing result, the stud 18, which is rigidly secured to the support 8, has rotarily mounted thereon a ratchet wheel 27. The hub of this ratchet wheel is spaced from the support 8 by a spacer roll 28 and a spring washer 29 and from the head of the stud 18 by a ratchet spring 30 held against rotation on the stud by fitting against a flat or slabbed off portion 31 and having its teeth 32 cooperating with recesses 33 on the opposed face of the ratchet wheel. Thus a light friction is imposed on the ratchet wheel and reverse rotation thereof prevented. The ratchet wheel presents a series of regular teeth, the number of which will determine the number of operations of the filling cutting mechanism, and a long tooth 34.

The shank 14 of the main cutter blade is provided with a laterally projecting lug 35 beneath the slot 16. The hub of the ratchet wheel 27 is radially extended at one side to form a detent cam 36 in vertical alignment with the lug 35. The cooperating faces 37 of the detent cam and 38 of the lug are relatively eccentric. In the specific construction illustrated to obtain this relative eccentricity, the center of curvature of the surface 38 of the lug lies in a line passing below the axis of the stud 18 which is the center of curvature of the surface 37 of the detent.

The ratchet wheel 27 which moves bodily forward and rearward with the support 8 is rotated by a pawl carried by a normally stationary, but forward and rearward movable, arm mounted on the loom frame. When the predetermined condition, upon the occurrence of which the intermittent action of the filling cutting mechanism is to take place, is that of filling replenishment, this arm 39 is conveniently secured to the starter rod 3. Thus the arm 39 is mounted on the frame, is normally stationary, but is movable forward and backward when filling replenishment takes place.

The pawl 40 is pivotally mounted at 41 on the arm 39 and is held in depressed position by a spring 42 forcing it against an adjustable stud 43, both the spring and the stud being seated in a portion 44 of the arm overhanging the pawl.

Normally the mechanism illustrated will stand as shown in full lines in Fig. 2 and in Fig. 6. In this position the shank 14 of the main cutter blade is held in its forward position by the detent cam 36 engaging the face

of the lug 35 and both cutter blades are in a position well forward of the fell. As the lay beats up, engages the heel 10 of the temple support 8 and moves this support slightly forward, the position of the parts remains unchanged because the upper face of the long tooth 34 of the ratchet wheel 27 slides under the pawl 40. When the predetermined condition occurs which is to set the filling cutting mechanism into operation and which in this case is the occurrence of filling replenishment, the arm 39 is moved forward or into the position shown in dotted lines in Fig. 2, carrying the pawl forward, swinging it slightly upward, and then allowing it to drop in front of the long tooth 34. Then upon the rearward movement of the arm 39, the pawl catching in front of the long tooth 34 gives a substantial angular movement to the ratchet wheel sufficiently to swing the detent cam 36 out of the path of the lug 35, thus allowing the spring 23 immediately to project the filling cutting mechanism rearward into operative position. Thereafter upon each beat-up of the lay, the filling cutting mechanism is operated in the usual manner to open and close upon the filling ends extending from the filling. But as each beat-up takes place, the lay engaging the heel 10 moves the support 8 slightly forward and the ratchet wheel 27 cooperating with the pawl 40 is rotated step by step. This continues, depending upon the number of teeth in the ratchet wheel, until the detent cam 36 again comes into a position where it begins to contact with the face of the lug 35. Thereupon the filling cutting mechanism is held in forward inoperative position. Owing to the relative eccentricity of the faces 37 of the detent cam and 38 of the lug, the final movement of the detent cam before the long tooth 34 comes into position to meet the pawl 40 cams the shank 14 slightly forward relatively to the support 8 to bring the depending heel 22 slightly forward of the depending heel and is as shown in Fig. 2. The advantage of this is that in the many beat-ups of the lay which take place between the required operations of the filling cutting mechanism, the lay which is the actuating means for the filling cutting mechanism cannot engage the heel 22 and so no movement whatever of the filling cutting mechanism takes place and it is saved entirely from unnecessary wear and tear.

Having thus described the invention, what is claimed as new, and desired to be secured by Letters Patent, is:

1. In a loom, a temple stand mounted on the frame, a temple support mounted in the stand and movable forward by the lay, a spring acting to move the temple support rearward, a main cutter blade having a shank mounted and rectilinearly movable on the temple support forward by the lay and rear-

ward by a spring, a lug on the shank, a co-operating cutter blade opened and closed upon the main blade by the movement thereof of forward and rearward, a ratchet wheel 70 rotarily mounted on the temple support having a long tooth and a detent cam cooperating with the lug, a normally stationary forward and rearward movable arm mounted on the frame, a pawl pivoted on the arm and overlying and cooperating with the ratchet wheel to rotate the ratchet wheel step by step 75 upon each lay-induced forward movement of the temple support until the long tooth comes beneath the pawl and the detent engages the lug to lock the main cutter blade in forward open position, and the said arm acting when thereafter moved forward and then rearward first to drop the pawl in front of the long tooth and then to cause the pawl to engage the long tooth and rotate the ratchet wheel 80 sufficiently to unlock the detent cam from the lug and permit the main cutter blade to move rearward to closed position.

2. In a loom, the construction defined in claim 1, in which both the temple and the main cutter blade are provided with depending heels in the path of the lay for effecting their forward movements from the lay, and in which the detent cam when in locking engagement with the lug maintains the cutter heel forward of the temple heel so as not to be struck by the lay when the cutter blades are inoperative.

3. In a loom, a support mounted on the frame yieldingly movable rearward and movable forward by the lay, filling cutting mechanism movably mounted upon the support to open and close upon filling ends extending from the selvage, a ratchet wheel rotarily mounted on the support having a long tooth 100 and a detent cooperating with the cutting mechanism, a normally stationary forward and rearward movable arm mounted on the frame, a pawl pivoted on the arm and overlying and cooperating with the ratchet wheel to 105 rotate the ratchet wheel step by step upon each lay-induced forward movement of the support until the long tooth comes beneath the pawl and the detent locks the cutting mechanism in an inoperative position, and the said arm acting when thereafter moved forward and then rearward first to drop the pawl in front of the long tooth and then to cause the pawl to engage the long tooth and 110 rotate the ratchet wheel sufficiently to unlock the detent cam from the cutting mechanism and free the cutting mechanism to operative position.

4. In a loom, the construction defined in claim 3, in which both the support and the cutting mechanism are provided with depending heels in the path of the lay for effecting respectively the forward movement of the support and the closing movement of the cutting mechanism and in which the de- 125 130

tent when holding the cutting mechanism in inoperative position maintains the heel of the cutting mechanism forwardly of the heel of the support so as not to be struck by the lay when the cutting mechanism is in inoperative position.

5. In a loom, the construction defined in
10 claim 1, in which both the temple and the
main cutter blade are provided with depend-
15 ing heels in the path of the lay for effecting
their forward movements from the lay, and
in which the detent cam and lug have rela-
tively eccentric cooperating faces acting to
move the main cutter blade slightly forward
15 with respect to the temple and, when in lock-
ing position, to maintain the cutter heel for-
ward of the temple heel so as not to be struck
by the lay.

6. In a loom, a support mounted on the
20 frame yieldingly movable rearward and
movable forward by the lay, filling cutting
mechanism bodily movable forward by the
lay and yieldingly movable rearward to open
25 and close upon filling ends extending from
the selvage, a ratchet wheel rotarily mounted
on the support having a detent cooperating
with the cutting mechanism, means cooperat-
30 ing with the ratchet wheel acting to rotate the
ratchet wheel step by step upon each of a pre-
determined series of lay-induced forward
bodily movements of the support and ratchet
35 wheel to bring the detent into position to lock
the cutting mechanism in forward inopera-
tive position and thereafter acting upon the
occurrence of a predetermined condition to
rotate the ratchet wheel sufficiently to bring
40 the detent into position to release the cutting
mechanism to operative position.

7. In a loom, the construction defined in
45 claim 6, in which both the support and the
cutting mechanism are provided with de-
pending heels in the path of the lay for ef-
fecting their forward movements from the
lay, and in which the detent and the por-
45 tion of the cutting mechanism cooperating
therewith have relatively eccentric cooperat-
ing faces acting to move the cutting mecha-
nism slightly forward with respect to the
50 support and, when in locking position, to
maintain the heel of the cutting mechanism
forward of the heel of the support so as not
to be struck by the lay.

In testimony whereof, I have signed my
name to this specification.

HORACE H. BURDETT.
